UNITED STATES PATENT OFFICE.

THEODOR LANGER, OF VIENNA, AUSTRIA.

AUTOMATIC AUXILIARY BLAST VALVE FOR LOCOMOTIVES.

Application filed October 8, 1924, Serial No. 742,445, and in Austria October 13, 1923.

This invention relates to an automatic auxiliary blast valve for locomotives, the valve of which is closed or opened by means of the piston of a steam-cylinder, in communication with the steam chest of the engine, on opening or closing of the regulator of the locomotive, whereby provision is made for regulating at will or shutting off the auxiliary blast whether the regulator is in the open or closed position.

In the known auxiliary blast valves of this kind the regulating and shut-off valves of the auxiliary blast are disposed in the admission portion of the steam main of the boiler. However this arrangement possesses the disadvantage that, in case the regulating valve is closed or throttled, the valve of the automatic valve is not at all, or only very slightly, loaded by the steam and is driven upward with great force when the regulator of the locomotive is opened and therefore is damaged very easily. A further disadvantage of the known automatic auxiliary blast valves of this kind consists in that in the operative position of the valve, for example in the position in which the auxiliary blast valve is automatically fully opened when shutting the regulator of the locomotive, the handle for operating the device is disposed in the middle between its two extreme positions, so that the handle has to be turned in one direction, in case it is desired to throttle or shut off the fully operative auxiliary blast arrangement, or in the other direction in case the last mentioned arrangement is to be placed in the operative position if the regulator is open, which requires a to and fro movement of the handle for the prevention of smoke if during the starting of the locomotive it becomes necessary for the auxiliary blast arrangement to remain in operation until the beginning of the continuous air draft.

The present invention has for its objects to remove these disadvantages and to simplify the construction.

One mode of carrying out the present invention is shown by way of example and in section on the accompanying sheet of drawing.

The live steam piping is connected to the branch 1 and leads from the branch 2 to the auxiliary blast device of the locomotive, while the piping of the steam chest of the engine is attached to the branch 3 and thus is in communication with the steam-cylinder

4. 6 designates the valve, which is operated by the piston 5. At the upper face the valve 6 is provided with a packing face 9, in order to establish a steam-tight closure 60 when seated upon the valve-seat 11 of the member 10. The valve 6 is furnished with a seat 7 in order to establish a steam-tight closure with a seat 8 when the valve is in the open position. The casing of the automatic valve is in communication with the casing of a hand-operated valve, which comprises three chambers 16, 17 and 18 arranged in axial alignment. A valve 19 is disposed in the middle chamber 17 and may be adjusted with respect to two valve-seats 21 and 22 by means of an adjustable valve-stem 27 adapted to be operated by a hand lever 28. The upper seat 22 of the valve 19 preferably cooperates with the seat of an axially adjustable member 23, the movement of which is limited by an adjusting screw 24, while at the bottom the said valve 19 terminates in a disc 20, which extends into the bottom chamber 18 and the diameter of 75 which corresponds to the diameter of a channel 25, establishing communication between the chambers 18 and 17. In the illustrated position of the valve the channel 25 is fully open, thus permitting free communication between chambers 17 and 18. This free passageway, however, may be reduced by adjusting the screw 24 so that the member 23 may be raised by the operation of the lever 28 to a higher position before abutting against the end of the screw 24. A passage 14 establishes communication between the chamber 12 of the automatic valve and the chamber 16 of the hand-operated valve, both chambers being disposed at the 80 steam supply side, and a passage 15 connects the discharge chamber 13 of the first mentioned valve with the middle chamber 17 of the last mentioned valve, so that even if the valve 19 is closed the automatic valve 100 6 is fully loaded by the steam and always is gently lifted on opening the regulator of the locomotive.

The apparatus operates in the following manner:

In the illustrated position of the lever 28, the valve 19 rests on the member 23 and the device is in the starting position. On opening the regulator of the locomotive, steam passes from the steam chest of the locomotive 110 by way of the branch 3 into the steam-cylinder 4 and the upwardly forced piston 5

presses the valve 6 onto the member 10 and thus shuts off the passage of the steam from the branch 1 to the branch 2, whereby the auxiliary blast arrangement is stopped. On closing the regulator the steam-cylinder 4 is emptied with respect to the steam chest of the engine and allows the valve 6 to pass into the open position, so that the auxiliary device is in the fully operative position.

10 After closing the regulator the extent of the auxiliary blast effect is determined by the position of the disc 20 with respect to the channel 25 which is regulated by the adjustment of the screw 24, so that the member 23 may be raised to a greater or less height in response to the operation of the hand lever 28, as hereinbefore described. On turning the handle 28 to the right hand side the valve 19 is forced onto the bottom seat 21, whereby the auxiliary blast device is throttled or shut-off. In case the valve 19 is disposed in a throttling position between the two valve-seats 21 and 22, the auxiliary blast device remains operative when opening the regulator of the locomotive until the lever 28 is turned to the left hand side into the illustrated position. Thus the advantage of the present invention consists not only in the most simple construction, but also in the possibility of a steam-tight shutting-off of the valve when the regulator is closed, further, in that the valve 6 is continuously evenly loaded by steam even if the hand-operated valve is shut and especially in that on opening the regulator the auxiliary blast effect is continued unhampered until it is stopped by moving the hand lever into the starting position.

I claim:—

- 40 1. An auxiliary blast valve for locomotives, comprising a housing having an inlet port adapted for communication with a source of steam supply, an outlet port adapted for communication with the auxiliary blast device of the locomotive and a port adapted for communication with the steam chest of the locomotive, partitions in said housing forming a chamber in communication with said inlet port, a chamber in communication with said outlet port and an intermediate chamber between said inlet and

outlet chambers, the partition between the inlet and intermediate chambers having two valve-controlled openings, a cylinder in communication with said steam-chest communicating port, a reciprocable piston in said cylinder, a valve automatically operable by said piston for closing one of said openings, the partition between the intermediate and outlet chambers being provided with a valve-controlled opening in axial alignment with the other of said first mentioned openings, an axially adjustable valve seat in said first mentioned opening, means for adjusting said valve seat, a double-acting valve for closing either of said aligned openings, and manually operable means for actuating said valve.

2. An auxiliary blast valve for locomotives, comprising a housing having an inlet port adapted for communication with a source of steam supply, an outlet port adapted for communication with the auxiliary blast device of the locomotive and a port adapted for communication with the steam chest of the locomotive, partitions in said housing forming a chamber in communication with said inlet port, a chamber in communication with said outlet port and an intermediate chamber between said inlet and outlet chambers, the partition between the inlet and intermediate chambers having two valve-controlled openings, a cylinder in communication with said steam-chest communicating port, a reciprocable piston in said cylinder, a valve automatically operable by said piston for closing one of said openings, the partition between the intermediate and outlet chambers being provided with a valve-controlled opening in axial alignment with the other of said first mentioned openings, an axially adjustable valve seat in said first mentioned opening, means for adjusting said valve seat, a double-acting valve for closing either of said aligned openings, a threaded stem for operating said double-acting valve, and a hand lever for rotating said stem.

In testimony whereof I hereunto affix my signature.

THEODOR LANGER.
